UNITED STATES PATENT OFFICE.

CHARLES L. KLAPPROTH, OF MIDLAND, TEXAS.

LEVEL.

1,403,606.

Specification of Letters Patent. Patented Jan. 17, 1922.

Application filed June 11, 1921. Serial No. 476,647.

To all whom it may concern:

Be it known that CHARLES L. KLAPPROTH, a citizen of the United States, residing at Midland, in the county of Midland and 5 State of Texas, has invented new and useful Improvements in Levels, of which the following is a specification.

This invention relates to levels and has for an object the provision of a stock composed of a plurality of angularly connected parts to permit the use of the device by carpenters, masons and other artisans to advantage on angular work as well as straight work.

15 A co-ordinate object of the invention is to provide a combined multipart stock and protractor co-operable to lay the angle or determine the plumb of the wall or other body upon which the device is used.

20 A further object of the invention is to provide a combination level the main part of the stock of which may be used in the capacity of the ordinary level and is equipped with sights, spirit levels, etc., which 25 may be used independently of or in conjunction with the auxiliary part of the stock, according to the nature of the work involved.

The above and other objects of the invention will be in part described and in part 30 understood from the following description of the present preferred embodiment of the invention taken in connection with the accompanying drawings wherein:

Fig. 1 is a side elevational view of a level 35 constructed in accordance with the invention.

Fig. 2 is a top plan view thereof.

Fig. 3 is a bottom plan view of the device.

Fig. 4 is an end elevational view of the 40 peep sight.

Fig. 5 is a similar view of the hair or wire sight.

Fig. 6 is a fragmentary plan view of the bar carried by the main part of the stock showing to advantage the terminal thereof.

45 The device of this invention consists of a stock generally designated 6 and consisting of a main part or body 7 and an auxiliary part or body 8. The proximate ends of these parts are tapered and equipped with two-way hinges 9 to permit relative lateral movement of the said parts in either direction.

The main stock 7 is equipped, intermediate its ends, with a vertical spirit level 10 of the usual or any desired design. A similar level 11 is counter-sunk in the top face of 50 the part 7 adjacent the inner end of the

latter. The upper face or margin of said main part 7 rises upwardly at its outer end, to provide a lift 12 upon which is mounted a hair or wire sight 13. Preferably the sight 60 is detachably mounted by means of a screw or the like as shown in Figure 2.

A bar 14 is detachably mounted upon the upper face of the part 7 of the level and has one end thereof extended with the free terminal thereof reduced to provide an annular terminus 15 which lies above the pintle of the hinges 9. Rising upwardly from the bar 14 adjacent to terminus 15 is a guide member 16 which slidably receives a peep 70 sight 17. The peep sight may be held in a desired position in the guide 16 by means of a nut and bolt 18.

Arranged upon the upper face of the auxiliary part 8 of the stock is a base plate 75 19 which is detachably mounted on said auxiliary part and has two ears 20 extended from the inner end thereof which are detachably engaged with the base of a protractor 21. The protractor has its upper 80 face suitably graduated with its arc slidably arranged beneath the bar 14. The inner marginal edge of said bar is bevelled, as indicated at 22, to facilitate reading of the indicia or graduations on the upper face of 85 the arc. A portion of the inner edge of the protractor base is extended at 23, as shown to advantage in Figure 3 and is formed to provide an annulus which extends upwardly through the terminus 15 of the bar 14. The 90 upper end of the annulus is swelled over the terminus 15 to prevent displacement of the bar 14 and insuring a more facile movement of the parts 7 and 8.

In order that the parts 7 and 8 may be 95 locked from movement when the desired angularity thereof has been obtained, a set screw 24 is provided which is arranged through the bar 14 and engages the main part 7 of the level. As shown to advantage 100 in Figure 2 the auxiliary body 8 of the stock may be turned at right angles to the part 7 if desired.

The auxiliary part 8 of the stock is provided with a horizontal spirit level 25 which 105 is preferably arranged midway the ends of said part 8 for use in an obvious capacity. Preferably the auxiliary part 8 is relatively smaller than the main part 7 but is of a height and thickness equal to the latter.

110 From the above, it will be apparent that the protractor is co-operable with the parts

of the level in order to lay the desired angle of a wall or the like and that the said parts may be held in any desired position. The sights and spirit levels of the device of course function in a manner well known in the art.

Various changes may be made in this device especially in the details of construction, proportion and arrangement of parts 10 within the scope of the appended claims.

What is claimed is:

1. A level including a pair of sections hingedly connected and having the proximate terminals thereof formed to provide 15 double beveled faces to permit said sections to move laterally in either direction to form a right angle or any fraction thereof.

2. A level including a main and auxiliary

hingedly connected sections, a base plate carried by the auxiliary section adjacent its hinge, a protractor secured to said base plate with its arc extended across the hinge point of the sections and slidable across the main section, and a guide plate carried by said main section and arranged over the protractor arc. 25

3. A level including hingedly connected level carrying parts one of which is relatively longer than the other, a base plate mounted upon the shorter part and equipped 30 with lateral extensions, and a protractor detachably secured to said extensions and slideable across said longer part of the level substantially as described.

CHARLES L. KLAPPROTH.
